UNITED STATES PATENT OFFICE.

AUGUSTINE S. McDERMOTT, OF DUBUQUE, IOWA.

CULTIVATOR.

SPECIFICATION forming part of Letters Patent No. 434,067, dated August 12, 1890.

Application filed February 17, 1890. Serial No. 340,742. (No model.)

To all whom it may concern:

Be it known that I, AUGUSTINE SYLVESTER McDERMOTT, a citizen of the United States, residing at Dubuque, in the county of Dubuque and State of Iowa, have invented certain new and useful Improvements in Cultivators; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

15 This invention pertains to certain new and useful improvements in cultivators, having for its object the production of a straddle-row cultivator, the parts of which can be adjusted and held close together or far apart.

20 The invention comprises improvements in the detail, construction, combination, and arrangement of parts, substantially as herein-after fully set forth, and particularly pointed out in the claims.

25 In the accompanying drawings, Figure 1 is a view in perspective of my improved cultivator. Fig. 2 is a detail view of the lever and its connection. Fig. 3 is a detail view of the connection between the arched bar and the drag-bar. Fig. 4 is a view of the front coupling for the latter. Fig. 5 is a view of the connection between the drag-bars and the cultivator-shovel standard. Figs. 6, 7, and 8 are detail views.

30 Referring to the drawings, A designates the arched axle; a, the divergent tongue-bars, secured to said axle; a', the doubletree, and a² the carrying-wheels, the treads of which are brought closer together or moved farther apart by cylindrical washers a³, inserted on the ends of said axle either before or after the wheels.

35 B B are the cylindrical drag-bars, having handles b. Their forward ends are each secured by a bolt b' in a split sleeve b² of a coupling or hinge b³, which is attached to the lower end of an arched hanger-bar b⁴ by a set-screw b⁶, working in a collar b⁷ of said coupling. The latter is provided with an upper curved loop b⁸, through which said hanger-bar projects, so as to permit of adjustment of said coupling. This coupling or hinge is reversible—that is, it can be used on the right or left hand

side, and thus the drag-bar can be brought closer together or held farther apart. The set-screw b² permits the coupling or hinge to be held at any point on bar b⁴.

C C are the cultivator-shovel standards, each of which is rigidly secured to a U-shaped bracket or clip D, having slotted arms d d, through which and holes in the drag-bars 60 are passed bolts d', washers d² being interposed between said arms and drag-bars. These washers are cylindrical, and provided on one face with intersecting grooves or recesses d³ d⁴, the latter being deeper than the former, whereby the standards on opposite sides of drag-bar can be set closer together or held farther apart, increasing or diminishing the distance between standards C on each drag-bar. Teeth d⁵ are formed in one face of 70 each washer to engage similar teeth on arms d to prevent slipping.

E E are two levers fulcrumed each at e on a frame e', secured to tongue-bars a. Said frame is provided with a slot e², through which projects a bolt e³ of lever E, a spring e⁴ and disk e⁵ serving to hold a pin e⁶ of such lever in engagement with any one of a series of apertures e⁷ in such frame. To the outward forward end of lever E is pivoted a plate F, 80 having hooks f f', to the former of which is connected one end of a chain f², secured to one end of a coil-spring f³, the other end of the latter being secured to a hook f⁴ of lever E. To hook f' is connected one end of a 85 chain G, the other end of which is secured to a hook g of a clamp g', attached to drag-bar B. These clamps g' have each loops g² for holding a cylindrical portion or arm g³ of a swivel g⁴. In these swivels are adjustably 90 connected the ends of an arched bar g⁵, the same being held by bolts g⁶, passed through apertures g⁷. This arch-bar serves to hold the drag-bars the desired distance apart. By means of lever E and its spring the drag-bar 95 can be held at the desired tension and the latter is readily adjusted to a greater or less degree. By inserting a wooden pin in opening f⁵ of plate F the latter can be held rigid when spring-tension is not required.

H is the seat adjustably secured on the rear end of a support for frame h, the forward ends of which latter are rigidly secured to plates h' h', pivoted to tongue-bars a and held ad-

justable by a bolt h^2 , inserted through any one of a series of holes h^3 . The operator's feet are designed to be placed in stirrups I, attached to the drag-bars. The seat can be 5 adjusted according to the weight and size of the driver or operator.

To axle A are secured hangers J, having rollers j , around which are passed chains j' , connected at their ends to rods $j^2 j^3$, secured 10 to bars $j^4 j^5$, connected to the outer ends of the doubletree a'. The bars j^4 are provided with a series of apertures j^6 to permit of different hitches to balance cultivator.

From the foregoing description it will be 15 seen that I have produced a cultivator composed of simple and highly-efficient parts which are capable of adjustment so that the shovels may be held closer together or farther apart, according to the width of the rows or 20 whether it is upon small or young corn the cultivator is operating or upon corn at last cultivation. It will also be observed that the parts are all interchangeable and are readily and easily secured together.

25 One of the most important features of my invention consists in the double hook secured to the ends of the levers and having spring-pressure connected to one section thereof and the connection with the drag-bar attached to 30 the other section. By moving the lever the tension of the spring is changed, and when the shovels are in operation the spring has but little control thereover; but when the drag-bars or shovels move upward the power 35 of the spring will hold the drag-bars in place without necessity for moving or adjusting the levers.

I claim as my invention—

1. In a cultivator, the combination, with 40 the drag-bars and the hanger-bars, of the coupling or hinge having a split sleeve encircling and secured to the forward end of each drag-bar, and an upwardly-extended collar secured to said sleeve and attached to the 45 lower end of one of said hanger-bars, and a set-screw for holding the same, substantially as set forth.

2. In a cultivator, the combination, with 50 the drag-bar and the hanger-bar, of the coupling or hinge consisting of a split sleeve encircling and secured to the forward end of said drag-bar, an upper curved loop, a collar, and a set-screw for attachment to said hanger-bar, substantially as set forth.

55 3. In a cultivator, the combination, with the cylindrical drag-bars, of the shovel-standards having U-shaped brackets or clips secured to opposite sides of said drag-bars and adjustable laterally with relation to their parallel sides, substantially as set forth.

4. In a cultivator, the combination, with the cylindrical drag-bars, of the shovel-standards, the U-shaped brackets or clips, the washers having each corresponding intersecting grooves or recesses of different depths, 65 and the nutted bolts, substantially as set forth.

5. In a cultivator, the combination, with the cylindrical drag-bars, of the shovel-standards located in opposite sides of said drag-bars, the brackets or clips having arms, the grooved washers interposed between said arms and drag-bars and the nutted bolts, substantially as set forth, whereby said shovel-standards can be held farther apart or closer 75 together.

6. In a cultivator, the levers having the pivoted plates at their forward ends, the springs connected to said levers and to said plates, and the connection between the latter and 80 the drag-bars, substantially as set forth.

7. In a cultivator, the combination, with the drag-bars, of the levers having each a pivoted plate at its forward end, the springs connected to said plate, and the chain-connections between said drag-bars and said plates, 85 substantially as set forth.

8. In a cultivator, the combination, with the tongue-bars, the slotted frame having holes or openings, and the drag-bars, of the 90 levers having pins designed to enter said holes or openings, the spring-pressure holding said levers against said frame, the plates pivoted to said levers, the springs connected to said levers and plates, and the connections 95 between the latter and said drag-bars, substantially as set forth.

9. In a cultivator, the combination, with the drag-bars, of the clamps having looped portions, the swivels having vertical portions 100 secured in said looped portions and provided with holes or openings in their upper horizontal portions, the arched bar, and the bolts for adjustably securing the ends of said bar in said swivels, substantially as set forth. 105

10. In a cultivator, the combination, with the tongue-bars, of the forked supporting-frame h, the seat adjustably secured on the outer end thereof, the plates h', rigidly secured to the forward ends of the bars of said frame and having a series of holes and pivoted to the tongue-bars, and the bolts h², for adjusting said plates with relation to said tongue-bars, substantially as set forth.

In testimony whereof I affix my signature 115 in presence of two witnesses.

A. S. McDERMOTT.
